DERRICK CONSTRUCTION

Arthur W. Lewis, La Canada, Calif., assignor to
Petroleum Derrick Co. Ltd., La Canada, Calif.,
a corporation of Nevada

Application March 7, 1932. Serial No. 597,120

2 Claims. (Cl. 189—13)

My invention relates to oil well derricks fabricated from structural steel members. Such derricks are in general use throughout the world and are fabricated by many manufacturers. All 5 of these manufacturers, so far as I am aware, have adhered closely to standard tower design, using four leg members connected by girts, which encircle the derricks, and diagonal cross bracing members, each member of which extends from 10 the junction of a girt with a leg to the junction of an adjacent girt on an adjacent leg, the cross bracing members crossing each other at approximately the center of the panel formed by the two girts and the two legs.

15 In steel derricks of all kinds with which I am familiar, including the derrick described herein, the corner legs are designed to carry the entire vertical load. In addition to this vertical load, such derricks are subjected to certain loads producing horizontal stresses in the derrick. Such 20 stresses for example are produced by the drill pipe which is not in use and which rests upon the derrick floor and leans against the upper portion of the derrick. Since several thousand 25 feet of pipe in long stands are constantly so stored, the horizontal component of force produced thereby on the derrick is considerable.

In addition to this component the derrick in 30 times of high wind is subjected to horizontal load- 35 ing due to this wind. In the conventional form of derrick the cross bracing in the panels formed by the legs and girts is depended upon to resist all horizontal load components. This cross bracing is always in tension and is not designed in such a manner as to have any material strength in compression.

It is an object of my invention to produce a 40 derrick in which the conventional cross bracing is eliminated and in which a novel arrangement of diagonal bracing is used. By this novel arrangement I am able to produce a derrick having the same ability to resist the forces to which a derrick is subjected as the conventional form of derrick but in which a considerable saving in 45 weight of material over that used in the conventional derrick is possible due to a better utilization of material.

In derricks of my invention the diagonal members are also depended upon to resist the horizontal load components imposed on the derrick, but these diagonal members are in compression. Derricks constructed in accordance with my invention are not only more economical in material used in their construction than conventional derricks but are much more rigid, due to the open

type of construction used, offer less wind resistance than the standard derrick, and due to a reduction in the number of parts and connections require less labor to fabricate and erect than a conventional derrick.

80 Further objects and advantages will be made evident hereinafter.

In the drawings which are for illustrative purposes only:

Fig. 1 is a diagram in pseudo-perspective, 65 showing the preferred form of derrick embodying my invention.

Fig. 2 is an elevation of the ladder and pump side of said derrick.

Fig. 3 is an elevation of the calf wheel side of 70 said derrick.

Fig. 4 is an enlarged view showing one method of connecting the various derrick members.

Fig. 5 is an elevation showing a center six point 75 connection.

Fig. 6 is a view showing a corner six point diagonal connection as it would appear were that portion of the structure shown to the left of the line *a—a* turned 90° towards the plane of the paper from its actual position.

Fig. 7 is a section through one of the legs.

Fig. 8 is a section taken as indicated by the line *b—b* of Fig. 6; this figure, however, is not distorted from its normal plane.

In the drawings I have illustrated a derrick 80 of the proportions usually employed in well drilling rigs, the derrick having four sides and being substantially larger at its base than at its upper end. I have illustrated a construction suitable for a derrick in the neighborhood of 120 feet 90 high and intended to carry various units of drilling equipment, such as a crown block, draw works, etc.

The derrick illustrated, being four-sided, includes four legs 10. In accordance with the present invention, horizontal girts 11 are provided at each side of the derrick to extend between the legs 10, diagonal members 12 are provided between the girts 11 and the legs 10, and various other features of construction are provided, as 100 will be hereinafter described.

The legs 10 of the derrick are located at the corners of the structure and extend from the base to the upper end. Each leg 10, in accordance with my invention, involves three principal parts, 105 namely, two main flanges 13 lying in the planes of the adjoining sides of the derrick, and an outer flange 14 projecting outwardly from the point of intersection of the main flanges 13. The main flanges together form an angle-shaped 110

structure, each main flange forming a part to which the girts and diagonal members of the structure may be connected. The outer flange 14 projects outwardly from the corner formed by the main flanges so that there are equal angles between the outer flange and the two main flanges, as clearly illustrated in Fig. 7 of the drawings. The outer flange 14, because of its relationship to the main flanges, adds a substantial amount of strength and rigidity to the leg by the addition of but little material to the structure formed by the main flanges alone.

In accordance with the preferred form of the invention, each leg is of sectional construction, i. e., the leg construction just described is in two sections, the line of division being through the center of the outer flange 14 in the plane of the outer flange, so that each leg section includes a main flange and an outer flange part 14^a. When the leg is assembled, as shown throughout the drawings, the flange parts 14^a abut and are secured together as by bolts 15, or the like. In practice, bolt holes are provided at suitable intervals throughout the lengths of the flange parts 14^a and the bolts 15 are applied to secure the flange parts 14^a together as the derrick is assembled. A feature of the sectional leg construction just described is that the sides of the derrick can be assembled on the ground in sections of suitable length and then moved into position to be secured by coupling the flange parts 14^a of the legs through the bolts 15.

In the structure of the present invention, there are several horizontal girts 11 at each side of the derrick. The girts 11 are arranged to extend between opposing main flanges 13 of the derrick legs and are vertically spaced. The girts 11 may be formed of angle iron and may be connected to the main flanges 13 of the legs through joints or connections such as I will hereinafter describe.

The invention provides a novel and effective arrangement of diagonal members 12 between the legs 10 and horizontal girts 11. In accordance with the invention, there are four diagonal braces 45 located in each space defined by adjacent legs of the derrick and adjacent girts 11 extending between said legs. The diagonal members 12 are connected to the opposing main flanges 13 of the said derrick legs at points intermediate the points of connection between the horizontal girts and the legs. Diagonal members A extend from their point of connection with the derrick legs upwardly and inwardly to a point where they adjoin each other and connect with the middle portion of the upper girt 11, while diagonal members B extend from their point of connection with the legs downwardly and inwardly to a point where they adjoin and connect with the lower girt 11. This arrangement of parts is clearly illustrated in Figs. 1, 2, and 3 of the drawings. The diagonal members A and B are preferably formed of angle iron and are connected with the leg flanges and the girts through connections such as I will hereinafter describe. In the case illustrated, the diagonal members are shown connected directly to the leg flanges 13 and are shown connected to gusset plates 16 attached to the horizontal girts by bolts 17. The diagonal members 12 of the construction are active or load-carrying parts of the structure and, when the derrick is under a strain, these members act either under compression or tension. By supporting the diagonal members 12 intermediate their ends, a given load capacity can be gained by the use of lighter members than

is possible if the members are free or unsupported between their ends. I may therefore brace or support the diagonal members 12 intermediate their ends by braces 18, as shown at portions of the derrick illustrated in the drawings. The braces 18, as illustrated in the drawings, are connected with the middle portions of the diagonal members and extend to points adjacent the points of connection between the horizontal girts 11 and the legs 10.

It is to be noted that the braces 18 that may be employed to permit of the use of light diagonal members are comparatively short and form but a small portion of the derrick structure.

The framing and bracing at the lower part of the derrick may vary considerably from the main derrick construction that I have hereinabove described in order to accommodate equipment such as may be employed in connection with the derrick. In the drawings, I have shown framing below the horizontal girts C suitable for units of equipment such as are commonly employed in the drilling of oil wells.

My present invention provides a joint or connection for coupling the ends of the angle iron members with the other parts, for instance, with the leg flanges and the gusset plates. In accordance with my invention, a reinforcing member 20 is applied to the end portion of the angle iron, being connected to the member, and a bolt 21, 105 or the like, connects the reinforcing member and one flange of the angle iron to the member to which the angle iron is connected, while a bolt 22 connects the reinforcing member with the other flange of the angle iron. The reinforcing member may be an angle-shaped part designed to fit into the angle iron and having flanges 23 fitting against the inner sides of the flanges of the angle iron. The main connecting bolt 21 which joins the angle iron to the member to 115 which it is to be connected joins two flanges and the reinforcing member to the angle iron. The bolt 22 joins the other flange of the angle iron to the other flange 23 of the reinforcing member. Through the medium of the reinforcing member 120 and the bolts 21 and 22, the second or otherwise unsupported flange of the angle iron is connected with the member to which the angle iron is connected, thus developing the strength of both flanges of the angle iron. In addition to the bolt 21, the reinforcing member 20, the angle, and the member to which the angle iron is connected may be connected through a lug 24 formed on one flange 23 of the reinforcing member to project 125 through registering openings 25 in the flange of the angle iron and the member to which the angle iron is attached. The lug 24 does not act to tie the parts together; however, it is effective with the bolt 21 in resisting shearing strain tending to 130 separate the parts, and it increases the load or strain taking bearing surfaces of the connected parts.

Through the sectional leg construction provided by my invention, sections or lengths of the sides of the derrick can be assembled on the ground and lifted into place, where they may be made secure by the bolts 15 joining the flange parts 14^a of the leg sections. It is to be noted that the outwardly projecting flange parts 14^a are angularly disposed so that a side section of the derrick can be readily moved inwardly into position so that it is guided by the flange sections 14^a of the adjoining sides of the derrick and that the leg parts requiring connection, i. e., the flange 145 150

parts 14^a, are located so that the bolts 15 can be readily applied.

It will be noted that the diagonal members 12 form six point (or member) connections at the 5 points indicated by the dotted circles at 100 and 101 in Fig. 1. The connections at point 100 are shown in Fig. 5, and the connections at point 101 are shown in Fig. 6.

Referring to Fig. 5 it will be seen that forces 10 are distributed from the point 102 in six directions, due to the six members which radiate from this point (the girt 11 acting as two of these members).

Referring to Fig. 6 it will be seen that forces 15 are distributed from the point 103 in six directions, due to the six members which radiate from this point (the leg 10 acting as two of these members).

The derrick in fact consists of legs and diagonal members, each of the diagonal members 20 terminating at each end in a six point connection.

These diagonal members differ from the conventional cross bracing found in all sorts of structures in that they act in compression to resist 25 horizontal forces.

It will further be noted that in the embodiment 30 of my invention, as shown in Fig. 6, the diagonals of one side are definitely positioned with relation to the diagonals of an adjacent side, that is all the diagonals at one end or the other terminate at a six point connection which is made up of the legs, two diagonals from one side and two diagonals from another side. This six point sys-

tem of bracing gives great stiffness to the derrick with a minimum use of material.

I claim as my invention:

1. In an oil well derrick, the combination of: four leg members; girt members arranged in sets of four extending around the derrick in the same plane and being connected at their ends to said legs; and diagonal members each extending from and connected to adjacent legs, said diagonal members being so placed that they form with the girts six point connections at the centers of said girts and that they form with the legs six point connections on said legs at a point midway between the planes of adjacent girts. 80

2. In an oil well derrick, the combination of: four leg members; girt members arranged in sets of four extending around the derrick in the same plane and being connected at their ends to said legs; diagonal members each extending from and connected to adjacent legs, said diagonal members being so placed that they form with the girts six point connections at the centers of said girts and that they form with the legs six point connections on said legs at a point midway between the planes of adjacent girts; auxiliary 95 braces substantially perpendicular to said diagonal members, each of said braces extending from the junction of a girt with a leg to a point on a diagonal brace midway between the girt and the leg; and means for securing one end of said 100 brace to said leg and the other end of said brace to said diagonal member. 105
